UNITED STATES PATENT OFFICE.

EMIL BLASBERG, OF DETROIT, MICHIGAN, ASSIGNOR TO JOHN H. CLAUSS, OF FREMONT, OHIO.

SHEARS.

SPECIFICATION forming part of Letters Patent No. 770,551, dated September 20, 1904.

Application filed February 13, 1904. Serial No. 193,380. (No model.)

To all whom it may concern:

Be it known that I, EMIL BLASBERG, a citizen of the United States of America, residing at Detroit, in the county of Wayne and State of Michigan, have invented certain new and useful Improvements in Shears; and I hereby declare the following to be a full, clear, and exact description of the invention, such as will enable others skilled in the art to which it pertains to make and use the same.

This invention relates to improvements in shears.

The object of this invention is to provide means for preventing the pivot-pin which secures the shear-blades together from working loose.

The invention therefore consists in providing a short arm which is secured to the blade in which is formed the screw-threaded bore which receives the screw-threaded end of the pivot-pin; and the free end of said arm intervenes between the other blade and the head of the pivot-pin, so as to entirely prevent or eliminate any friction between the last-mentioned blade and the said pivot-pin.

My invention also consists in the features of construction and combination of parts, as described in the specification, pointed out in the claims, and illustrated in the drawings.

In the accompanying drawings, Figure 1 is a view of a shears embodying the invention in the preferred form. Fig. 2 is a section on line 2 2, Fig. 1.

In the accompanying drawings, 1 represents the shear-blade, in which is formed a screw-threaded bore 2 for receiving the screw-threaded end of the pivot-pin 3, which secures the blades together. The other blade, 4, is provided with a smooth bore 5, so that it turns freely on the pivot-pin 3, while the pin 3 remains stationary in the blade 1. In my preferred construction the bore 5 in the blade 4 is formed larger than the bore 2 in the blade 1.

9 represents a short arm, preferably of steel or other resilient material, which is secured to

the blade 1 by means of two small flanges 10 and 11, which engage the reduced or handle portion 14 of the said blade 1. In the arm 9 is formed a bore 6, around which is arranged 50 an annular flange 7, which extends into the bore 5 in the blade 4 and forms a bearing-ring on which the said blade 4 turns.

It will readily be seen that as the arm 9 intervenes between the head of the pivot-pin 55 and the blade 4 the movement of the blade 4 will not have any tendency to loosen the pivot-pin and as the arm is secured on the blade 1 the pivot-pin will of course move with the said blade, and therefore the movement of the 60 blade 1 will have no tendency to loosen the said pivot-pin. Also if the pivot-pin should be loosened in any manner, as by dropping the shears, the resilient arm will hold the blade 4 against the blade 1 until the pivot-pin can 65 be tightened.

What I claim is—

1. A shears comprising a blade, a pivot-pin screwed into said blade, a blade having a pivot-pin hole larger in diameter than said pivot- 70 pin mounted on said pivot-pin, a bearing-ring arranged in the pivot-pin hole of the last-mentioned blade so as to intervene between said last-mentioned blade and the pivot-pin, and means for securing said bearing-ring to the 75 first-mentioned blade to prevent said bearing-ring from turning on the pivot-pin.

2. A shears comprising a blade, a pivot-pin screwed into said blade, a blade having a pivot-pin hole larger in diameter than said pivot- 80 pin mounted on said pivot-pin, a bearing-ring arranged in the pivot-pin hole in the last-mentioned blade so as to intervene between said last-mentioned blade and said pivot-pin, said bearing-ring being provided with a seat for 85 the head of said pivot-pin and means for securing said bearing-ring to the first-mentioned blade to prevent said bearing-ring from turning on the pivot-pin.

3. A shears comprising a blade, a pivot-pin 90 screwed into said blade, a blade, having a pivot-pin hole larger in diameter than said pivot-

pin, mounted on said pivot-pin, a bearing-ring arranged in the pivot-pin hole so as to intervene between the said last-mentioned blade and the pivot-pin and an arm formed integral with said bearing-ring, substantially as described and for the purpose set forth.

In testimony whereof I sign the foregoing

specification, in the presence of two witnesses, this 5th day of January, 1904.

EMIL BLASBERG.
